UNITED STATES PATENT OFFICE.

ARTHUR LEGBAND, OF SCRIBNER, NEBRASKA.

HAY-TRUCK.

1,381,479.

Specification of Letters Patent. Patented June 14, 1921.

Application filed June 3, 1920. Serial No. 386,291.

To all whom it may concern:

Be it known that I, ARTHUR LEGBAND, a citizen of the United States, residing at Scribner, in the county of Dodge and State 5 of Nebraska, have invented a new and useful Hay-Truck, of which the following is a specification.

The present invention has reference to agricultural trucks, and more particularly 10 to a novel truck for lifting or moving hay stacks or the like in a manner to maintain the stack in its usual compact form, to the end that the space required to store the hay or feed, is reduced to a minimum.

15 An object of the invention is to provide a device of this character having lifting prongs adapted to be forced through the stack under operation, thus insuring against the stack becoming displaced from the truck 20 while the same is being moved.

A further object of the invention is to provide novel means for forcing the lifting prongs into the stack so that the same will be firmly secured therein.

25 With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

35 Referring to the drawings:—

Figure 1 illustrates a plan view of one portion of the truck, disclosing the lifting prongs, a stack being shown in outline, by the dotted lines.

40 Fig. 2 illustrates a plan view of one section of the truck.

Fig. 3 illustrates a side elevational view showing the sections of the truck as assembled, and

45 Fig. 4 illustrates a front elevational view of the same.

Referring to the drawings in detail, one section of the truck is indicated generally by the reference character 5, and which includes the beam 6 which supports the usual 50 axle indicated at 7 and on which the wheels 8 are positioned, the wheels 8 being however provided with relatively wide tread surfaces to permit the truck to be easily moved over a field.

Secured to the beam 6, at opposite ends

thereof, are the lifting prongs 9, which have one of their respective ends fastened to the beam 6 by means of the securing members indicated at 10, so that the lifting prongs 60 will move with the beams 6.

The forward extremities of these lifting prongs 9 are tapered as at 11 to provide piercing ends to permit the prongs 9 to enter a stack and pass therethrough, when the device is brought into operation. In order 65 that these lifting prongs 9 may be maintained in proper spaced relation with each other, the bracket bars 12 are provided, which bars have connection with the beam 6, as by means of the bolt 13 and have connection with the prongs 9 as by means of the bolts 14.

Secured to each of the prongs 9 adjacent the inner ends thereof, are the eye bolts 15 75 which accommodate the hook members 16 that have connection with the pulleys 17 over which operate the flexible member 18, to be hereinafter more fully described.

Each of the pulleys 17 is supported in a 80 frame, which is apertured to receive the ends of the flexible member 18, intermediate portions thereof passing over the pulleys 19 and 20 which are secured to the auxiliary flexible member 21, and which in operation 85 is adapted to embrace a portion of the stack, under operation, and which for convenience and a clear illustration of the operation of the device, is indicated in dotted lines and represented by the reference character 22. 90

The forward section of the truck includes a beam 23 which is provided with a suitable axle for supporting the wheels 24, the beam 23 being provided with cleats 25 for securing the fifth wheel 26 to the truck, the upper 95 or body portion of the section being indicated by the reference character 27, and has connection with the fifth wheels 26 through the arms 28 which support the body portion 27 in spaced relation with the beam 23. 100

The body portion 27 is braced by the frame 29, and has links 30 disposed adjacent to the respective ends thereof, which links 30 provide means for connecting the hook members 31 to the body portion 27, and which hook members when in operation, are adapted to coöperate with the clevises 32 which are connected to the lifting prongs 9 adjacent to the tapered extremities thereof. 105

The usual wagon tongue indicated at 33 110 has connection with the beam 23, and provides means for attaching a power means to

the truck for accomplishing the moving thereof, after a stack has been placed thereon. Supported by the body 27, is a hook member 34 that is associated with a bar 35 extending at an angle with relation to the body 27 and the tongue 33, there being provided an arm 36, which is secured adjacent to the tongue 33, the arm acting as a guide for the chain 37 employed for lifting the forward section of the truck.

It might be further stated that hook elements 38 are provided on the rear section of the truck which are adapted to accommodate the flexible member 18, to permit the same to be secured against movement, when the same has been drawn around a stack.

In the operation of the device, the flexible member is placed around a stack in a manner as indicated by Fig. 1 of the drawings, whereupon power is applied to the flexible member 18 at the attaching member 39 thereof, with the result that the prongs 9 are moved into engagement with the stack 22. It follows that upon further movement of the prongs 9, they are forced through the stack 22, the piercing ends 11 of the prongs 9 extending to a point beyond one plane of the stack 22. The clevises 32 are now applied to the prongs, and the body portion 27 of the front section of the truck moves to a position as indicated by dotted lines in Fig. 3 of the drawings, whereupon the hook members 31 are positioned in the clevises.

Power is now applied to the chain 37 to cause the body portion 27 to move upwardly to a position as indicated in full lines by Fig. 3 of the drawings, with the result that

the stack is lifted bodily, and is now in a position to be moved.

Having thus described the invention, what is claimed as new is:—

1. In a truck, a rear section and a forward section, said rear section having a pair of lifting prongs, means for forcing the lifting prongs through a stack, said forward section including a body portion, depending hook members carried by the body portion, clevises having connection with the prongs, and said hook members adapted to engage within the clevises for lifting the lifting prongs and supporting the same in spaced relation with the ground surface over which the truck is adapted to move.

2. In a truck, a rear section and a forward section, a pair of prongs carried by the rear section and having piercing ends, means for moving the prongs through a stack, said forward section having a body portion, a hook member carried by the body portion, said forward section adapted to be tilted to permit the body portion thereof to lie in close proximity to the lifting prongs, means having connection with the hook member, for moving the body portion to an operative position, and means for connecting the forward ends of the lifting prongs to the forward section.

In testimony that I claim the foregoing as my own, I have hereto affixed my signature in the presence of two witnesses.

ARTHUR LEGBAND.
